S. L. WAREHAM AND J. F. PANZNER,
OVERHEAD ROTARY VALVE FOR INTERNAL COMBUSTION ENGINES,
APPLICATION FILED NOV. 24, 1919.

1,384,416.

Patented July 12, 1921.

UNITED STATES PATENT OFFICE.

SAMUEL L. WAREHAM AND JOSEPH F. PANZNER, OF DETROIT, MICHIGAN.

OVERHEAD ROTARY VALVE FOR INTERNAL-COMBUSTION ENGINES.

1,384,416.

Specification of Letters Patent. Patented July 12, 1921.

Application filed November 24, 1919. Serial No. 340,367.

To all whom it may concern:

Be it known that we, SAMUEL L. WAREHAM and JOSEPH F. PANZNER, citizens of the United States of America, residing at Detroit, in the county of Wayne and State of Michigan, have invented certain new and useful Improvements in Overhead Rotary Valves for Internal-Combustion Engines, of which the following is a specification, reference being had therein to the accompanying drawings.

The primary object of our invention is to provide a rotary valve that may be advantageously used as the inlet and exhaust valve of an internal combustion engine, the valve being constructed so that the exhaust gases may be utilized for heating walls of a chamber containing an explosive mixture for the engine, the heat being by conduction and sufficient to increase the efficiency of the explosive mixture as a fuel for the engine. By heating or drying out the explosive mixture it is placed in a better condition for ignition, insures a less amount of carbon deposit in an engine cylinder, and affords practically instantaneous combustion without any slow burning in the cylinder which is liable to cause lagging in the timed operation of a multicylinder combustion engine.

Another object of our invention is to provide a novel overhead valve body with a rotary valve arranged to revolve with minimum friction and disposed so that it may be positively driven without any material leakage and without any overheating during the operation of an engine served by the rotary valve.

A further object of our invention is to provide a valve construction wherein the parts are constructed with a view of reducing the cost of manufacture and at the same time retain those features by which safety, durability, and ease of assembling are secured. With such ends in view, our invention resides in the novel construction to be hereinafter considered and then claimed.

Reference will now be had to the drawing, wherein—

Figure 1 is a vertical cross sectional view of a valve body and valve in accordance with our invention;

Fig. 2 is a longitudinal sectional view of the same;

Fig. 3 is a plan of the valve body with the cover thereof removed;

Fig. 4 is a plan of a detached valve;

Fig. 5 is an end view of the same;

Fig. 6 is an end view of a three-way connection adapted to be attached to the valve body, and

60

Fig. 7 is a side elevation of the same.

In the drawing, the reference numeral 1 denotes a substantially rectangular water jacket having a circular base 2 adapted to be mounted on an engine cylinder or cylinder block and retained thereon by tie rods or bolts 3 extending through vertically disposed and suitably spaced bosses 4 on the inner walls of the water jacket 1. The rods or bolts 3 are employed for retaining a cap or cover 5 on the water jacket 1, and said cap or cover has a water inlet connection 6 by which water or a cooling agent may be admitted to the jacket 1.

The circular base 2 of the water jacket 1 has a dome 7 adapted to close the upper end of a cylinder and this dome has a single walled passage or ported rib 8 which cooperates with other ribs 9 and 10 in supporting a cylindrical valve body 11 within the water jacket 1 and in spaced relation to the inner walls thereof so that the cooling agent may surround the valve body 11.

The ends of the water jacket 1 have cylindrical flanges or collars 12 and 13, with the latter provided with a peripheral flange 14 to which is suitably connected a three-way connection 15 which in turn supports an exhaust pipe 16.

Journaled in the valve body 11 is a cylindrical valve 17 having a short reduced end 18 and a long reduced end 19. Mounted on the short reduced end 18 of the valve body 17 is a hub portion 20 of a worm wheel 21 representing a conventional form of power transmission wheel or device, the worm wheel 21 being employed for imparting a rotary movement to the valve 17 within the valve body 11. The wheel 21 has its hub portion 20 connected to the end of the valve 17 by screw bolts 22 or other fastening means, and a series of anti-frictional rollers 23 are located in the collar 12 about the hub portion 20 of the wheel 21. With the wheel 21 abutting the end of the collar 12 the longitudinal movement of the valve 17 is limited in one direction, and said wheel is also employed as a closure member for a cylindrical longitudinal passage or bore 24 concentrically of the valve 17.

The opposite end of the valve body 17 is surrounded by anti-frictional rollers 25

110

within the collar 13 and the long reduced end 19 of said valve extends through the three-way connection 15 into the exhaust pipe 16, said reduced end of the valve being 5 surrounded by a split packing ring 26 within the outer end of the three-way connection 15, so as to form a closure between the end of the three-way connection and the long reduced end of the valve, as best shown in 10 Fig. 2. The packing ring 26 may be of a conventional form and this is also true of the anti-frictional rollers 23 and 25 which constitute anti-frictional bearings so as to insure a minimum friction when the valve 17 15 is revolved in its valve body. The valve 17 is of novel construction with the bore 24 thereof surrounded by communicating chambers 27 and these chambers are adapted to have the inner walls thereof heated by ex- 20 haust gases passing out of the bore 24, the heating of the chamber 27 being conduction. The valve body 17, intermediate the ends thereof, is formed with diametrically opposed exhaust ports 28 constantly communicating with the bore 24 and adapted to alternately communicate with the ported rib 8 communicating with the dome 7, so 25 that an engine cylinder may exhaust through the ported rib 8, the ports 28, and the bore 24 into the exhaust pipe 6. Between the ports 28 the outer wall of the valve 30 17 has ports 29 adapted to establish communication between the chambers 27 and the ported rib 8, so that an explosive mixture 35 which has been heated within the chambers 27, may be admitted to an engine cylinder. The explosive mixture is admitted to the chambers 27 by the three-way connection 15 and as the explosive mixture passes from 40 this three-way connection into the valve it impinges against the walls of the long reduced end 19 of said valve, and encounters its first heated surface before passing through the chambers 27 which are within 45 the body of the valve 17 and formed by the inner and outer walls of the valve which are maintained in spaced relation by connecting webs or ribs in addition to the walls of the ports 28 and 29.

50 Adjacent the ends of the valve 17 are suitable packing rings 30 and to lubricate the valve 17 some of the ribs 10 are ported, as at 31, to communicate with a lubricant chamber 32 mounted on the side of the water jacket 1, said lubricant chamber being supplied with oil or a suitable lubricant which

may be fed to the valve body 11 by gravity or of a force feed lubricant system.

From the foregoing it will be noted that during each revolution of the rotary valve 60 17 there are two communications with the ported rib 8 for exhaust purposes, and two communications for intake purposes, and during such an operation there is no danger of the valve being jammed or becoming accidentally displaced.

It is thought the operation and utility of our construction will be apparent without further description, and while in the drawing there is illustrated a preferred embodiment of our invention, it is to be understood that the structural elements are susceptible to such variations and modifications as fall within the scope of the appended claim.

What we claim is:—

A rotary valve comprising a valve body having a port adapted to communicate with the cylinders of an internal combustion engine, collars at the ends of said valve body, a three-way inlet connection carried by one 80 of said collars, an exhaust pipe connected to said three-way connection, a valve rotatable in said valve body having short and long reduced ends, and an exhaust bore throughout the length thereof, the long reduced end of said valve extending through said three-way connection into said exhaust pipe, a packing member about the long reduced end of said valve adjacent the exhaust pipe, said valve having opposed ports there- 85 in communicating with the exhaust bore thereof, said valve having chambers therein about the bore to be heated by the walls of the bore and the chambers communicating with said three-way connection, said valve 90 having chamber ports to communicate with the port of said valve body, a power transmission wheel having a hub portion fitted on, the short reduced end of said valve within said valve body and closing said bore and the 100 other of said collars, and anti-frictional bearings in both of said collars against said valve and retained therein by the power transmission wheel and said three-way connection.

In testimony whereof we affix our signatures in presence of two witnesses.

SAMUEL L. WAREHAM.
JOSEPH F. PANZNER.
